CHARLES E. FISK, OF NEW YORK, N. Y.

Letters Patent No. 90,518, dated May 25, 1869.

IMPROVEMENT IN PRINTERS' SHEARS.

The Schedule referred to in these Letters Patent and making part of the same.

To all whom it may concern:

Be it known that I, CHARLES E. FISK, of the city and county of New York, and State of New York, have invented a new and improved Mode of Cutting Printers' Plain Brass Rule; and I do hereby declare that the following is a sufficiently full, clear, and exact description thereof, to enable one skilled in the art to which my said invention appertains, to make and use it, reference being had to the accompanying drawings, which form part of this specification.

Printers' plain brass rule, cut by common printers' shears, when put up in rule-work, leaves a space between the end of the rule and bevelled edge of the cross-rule.

To avoid this space or break between the end of the rule and the bevelled edge, printers, in fine work, sometimes file down the end of the rule, so as to leave a mitred point, which fills out this space.

The nature of my invention consists in a mitre and a holder attached to common printers' shears or rule-cutter, by which the rule is held in place and the end cut off at one motion, leaving the mitred point complete. The mitre, being bevelled corresponding to the bevelled edge of the rule, does not curl the face of the rule in cutting.

Figure 1 represents the shears.

Letter *a* represents the mitre.

Letter *a'* represents the cavity which the mitre enters to cut the mitre-point.

Letter *c* is a projection to strengthen the cavity.

Letter *b* represents the gauge or holder by which the rule is held in place while cutting.

Figure 2 represents a vertical section of the shears, showing the mitre marked *a*, the cavity which the mitre enters marked *a'*, and *c* the projection.

Figures 3, 4, and 5, represent the different projections of the mitre marked *a*, viz, the side, front, and top.

Figure 6 represents a plain rule cut with a mitre-point.

This improvement can also be applied to printers' common rule-cutter, the principle and movement of the cutter being similar to the shears.

I claim, in combination with printers' shears or rule-cutter of otherwise ordinary construction, the mitre-cutter *a*, with corresponding indentation *a'* and the gauge or holder *b*, substantially as described and for the purposes specified.

CHARLES E. FISK.
